UNITED STATES PATENT OFFICE.

MAX KLENETZKY, OF NEW YORK, N. Y.

NURSING-BOTTLE SUPPORTER.

1,304,066.

Specification of Letters Patent.

Patented May 20, 1919.

Application filed October 18, 1917. Serial No. 197,207.

To all whom it may concern:

Be it known that I, MAX KLENETZKY, a resident of the city of New York, in the county of Kings and State of New York, have invented a certain new and useful Nursing-Bottle Supporter, of which the following is a specification.

This invention relates to devices that are utilized in connection with baby carriages for the purpose of facilitating and rendering convenient the feeding of babies with the usual nursing bottles. The principal object of my invention is to provide a simplified, inexpensive, and improved nursing bottle supporter that can be readily, rapidly, and conveniently attached to and detached from the baby carriage; which when the bottle is not in use will at all times maintain it in inoperative position entirely out of the way and will itself remain unobtrusive; and which after the baby has lost hold of the bottle-nipple, will prevent the bottle from rolling away and will enable the baby to again grasp it and return it to its mouth.

Other objects and advantages will hereinafter appear.

In the accompanying drawings.

Figure 1 is a plan view of the nursing bottle supporter, showing a bottle held thereby in operative state.

Fig. 2 is an elevation of the nursing bottle supporter shown in Fig. 1.

A nursing bottle 1 is held by a set-screw 35 2^a in a circular frame or collar 2 that is pivoted at 3 to a flexible arm 4 which extends to a fitting 5 that is fastened to the frame work 6 of the side of a baby carriage, not shown. The arm 4 consists of links or sections 7 that are hinged to each other at 8, and the last link of which is secured to the fitting 5. Said fitting is fastened in place by means of a thumb-screw 9 threading therethrough against the carriage frame 6, 45 the screw threading through a wing 10 of a strap-portion 11 of the fitting and causing an opposite wing 12 to bind against the carriage-frame 6. To the fitting 5 is secured a stem 13 about which is hinged a cylindrical casing 14 comprising a pair of halves 15, each of which is hinged about the stem 13. The casing-halves 15 may be swung about the hinge-stem 13 away from each other, as shown in Fig. 1, and they are normally drawn toward each other by a spring 16 secured to each of the casing-halves at

17. Pivoting of the arm-sections 7 to each other permits extension of any amount or portion of the arm 4 and thereby enables lateral adjustment of the bottle 1 to any 60 position nearer to or farther from the carriage-side 6, and when said bottle is thus adjusted the arm 4 is maintained longitudinally extended in horizontal state, Fig. 1, and holds the bottle in adjusted position. 65 Should any pull or pressure, however, be applied at the nipple 20 over the mouth of bottle 1, the arm 4 is sufficiently flexible to permit bending thereof and to thus give way either upwardly or downwardly or diagonally or universally in any direction. The remaining portion 19 of the arm 4 which is not in extended position is retained in folded state upon the fitting 5, by means of piling the sections 7 thereof on top of 75 each other, Fig. 2, and the spring 16 drawing the casing-halves 15 together so that their edges 18 intervene between the last extended link 7^a and the folded arm-sections at 19, thereby preventing the latter 80 links from being accidentally extended. After the baby has been fed and the nursing bottle is not in use all of the extended arm-sections 7 may be folded upon the pile 19 and within the casing-halves 15, whereupon the casing-halves will be drawn together closer by the spring 16 and caused to completely incase or inclose the entire arm 4 in locked folded state therewith and to retain the frame 2 with the bottle 1 there- 90 against and adjacent to the carriage-side 6, whereby the nursing bottle will be thus maintained safely and conveniently in place out of the way of the baby and without obstructing the various articles in the carriage. 95

When utilizing the supporter, its fitting 5 is secured to the carriage-side 6 in such position that the nipple 20 may be conveniently brought to the baby's mouth, and then 100 the bottle 1 is adjusted laterally, by ample extension of arm 4 to bring the nipple into the baby's mouth, leaving the remainder of the arm in locked folded state within the casing 14, as shown. It will be evident that 105 should the baby move its head and mouth in any manner, while feeding from the nipple 20, the arm 4 will allow the bottle to swing or move freely longitudinally, angularly, or laterally as may be required, and during all 110 such movement of the baby's head and of the bottle along therewith, the supporter will

continue to maintain the bottle in operative state at its mouth and in connected relation with the supporter. Should the baby however let go the nursing bottle altogether, it 5 would continue to be maintained by the extended arm 4 in operative state, enabling the baby to grasp said arm and thereby take hold of the bottle to again return the nipple to its mouth. After utilizing the supporter 10 its arm 4 can be completely folded and locked within the casing 14, and the supporter can be then readily detached from the carriage entirely, by merely untightening the thumb-screw 9.

15 Variations may be resorted to within the scope of the invention.

Having thus described my invention, I claim:

20 1. A nursing bottle supporter having the combination with means for attaching it to and detaching it from a baby carriage, of a flexible arm for holding the bottle in operative state adaptable to be folded, and a retaining casing having means to open and 25 close for inserting and closing said arm therewithin in folded state.

2. A nursing bottle supporter having the combination of an arm which is flexible and also extensible for holding the bottle in operative state adaptable to be folded, and a casing comprising two halves thereof hinged to each other and adapted to open and close for inserting and closing said arm therewithin in folded state.

3. A nursing bottle supporter having the combination of an arm which is flexible and also extensible for holding the bottle in operative state adaptable to be folded, a casing comprising two halves thereof hinged 10 to each other and adapted to open and close for inserting and closing said arm therewithin in folded state, and a spring drawing said casing-halves together to lock said arm therewithin.

4. A nursing bottle supporter having the combination with means for attaching it to

and detaching it from a baby carriage, of an arm which is flexible and also extensible for holding the bottle in operative state adapted to be partially folded and partially 50 extended, a casing comprising two halves thereof hinged to each other and adapted to open and close for retaining the folded portion of said arm therewithin while the remainder thereof is in extended state, and 55 means to lock said casing-halves in closed state.

5. A nursing bottle supporter having the combination with means for attaching it to and detaching it from a baby carriage, of a 60 universally flexible and extensible arm for holding the bottle in operative state adapted to be partially folded and partially extended, a casing comprising two halves hinged to each other and adapted to open 65 and close for retaining the folded portion of said arm therewithin while the remainder thereof is in extended state, and a spring drawing said casing-halves toward each other to lock the folded portion of said 70 arm in folded state.

6. A nursing bottle supporter having the combination of a universally flexible arm for holding the bottle in operative state comprising a plurality of sections hinged to each other and adapted to be partially folded and partially extended, a casing comprising two halves hinged to each other and adapted to open and close for retaining the folded portion of said arm therewithin 75 while the remainder thereof is in extended state, and a spring drawing said casing halves toward each other to lock the folded portion of said arm in folded state.

Signed at the city of New York, in the 80 county of New York, and State of New York, this 9th day of October, A. D. 1917.

MAX KLENETZKY.
